United States Patent Office

Des. 185,969

Patented Aug. 25, 1959

185,969

WATCH OR SIMILAR ARTICLE

Adolph Katz, Providence, R.I.

Application March 12, 1959, Serial No. 54,965

Term of patent 7 years

(Cl. D42—8)

Fig. 1 is a plan view of a watch or similar article showing my new design.

Fig. 2 is an edge view thereof.

The dominant feature of my design resides in the portions shown in solid lines.

I claim:

The ornamental design for a watch or similar article, substantially as shown and described.
